KNITTED FABRIC

Ivan W. Grothey, Laconia, N. H., assignor to
 Scott & Williams, Incorporated, New York,
 N. Y., a corporation of Massachusetts

Application April 28, 1933, Serial No. 668,457

2 Claims. (Cl. 66—201)

This invention relates to a knit fabric and particularly to a fabric such as is used in hosiery formed by knitting yarns in plating relation and it is an object of this invention to provide a fabric in which, by suitable combinations of wrapping, facing and backing yarns, suitable and attractive patterns may be formed.

In the drawings:—

Fig. 1 is a view in elevation of a stocking embodying fabric knit in accordance with this invention;

Fig. 2 is a view of a portion of a stocking leg with the patterns shown in Fig. 1 indicated thereon;

Fig. 3 is a view of a portion of a stocking leg having thereon patterns formed in accordance with this invention but differing from the patterns shown in Figs. 1 and 2; and

Figs. 4, 5, 6, 7 and 8 are enlarged views of the knit loops on the lines 4—4, 5—5, 6—6, 7—7 and 8—8 respectively of Fig. 3 showing the relative positions in the various loops or stitches of the various yarns used in forming the patterns shown in Figs. 1, 2 and 3.

In Fig. 1 there is shown a stocking the body of the leg L and instep I of which is formed of two yarns, a backing yarn and a facing yarn, knit in plating relation, and associated with said plated yarns is one or more embroidery or pattern yarns fed to selected needles in a wrapping relation in order to form the desired patterns. In Figs. 1, 2 and 3, for the purpose of illustration, the wrapping yarns are shown as forming pattern figures comprising stripe portions S and hollow figure portions f¹, f², f³, but it will be understood the invention is not limited to the particular designs shown. Within each of the hollow figure portions f¹ and f² there is a fabric l¹ formed of the backing and facing yarns identical with the fabric of the body of the stocking and fabric l² knit of only one of the yarns used in knitting the body of the leg of the stocking. In the illustration given, the backing yarn is used alone to form the fabric l², so as to contrast with the fabric l¹. In the figure portion f³ the fabric l² is also knit of the body yarn only.

In Figs. 4 to 8 inclusive, only sufficient wales have been shown in each course to clearly illustrate the relations of the yarns and it is to be understood that the numbers of wales to which particular yarns are fed in each course may be varied. In Fig. 4, which shows the arrangement of yarns for forming the pattern stripe portion S as at the line 4—4 of Fig. 3 and the lines 4'—4' and 4''—4'' of Fig. 2, the loops of a number of

wales, as 1 to 5 inclusive, are formed of a backing yarn b and a facing yarn p, which are fed in such plating relation that the facing yarn p appears on the face of the fabric. In a number of wales, as 6 and 7, a wrapping yarn w is knit with the backing yarn b while the facing yarn p is floated past these wales. At the line 4''—4'' of Fig. 2 the number of wales would be greater than at the lines 4—4 of Fig. 3 and 4'—4' of Fig. 2. In the following wales the facing yarn p is again knit with the backing yarn b as in wales 8 to 13 inclusive.

In Fig. 5, the backing yarn b and the facing yarn p are used in forming the loop of wale 1; the wrapping yarn w is knit with the backing 15 yarn b in forming the loops of wales 2 and 3 while the facing yarn p is floated; the facing yarn p is knit with the backing yarn b in forming wales 4 to 9 inclusive, and the wrapping yarn w is floated; the wrapping yarn w is knit with the 20 backing yarn b in forming wales 10 and 11 and the facing yarn p is floated; and the facing yarn p is knit with the backing yarn in forming wales 12 and 13, the wales 2, 3 and 10, 11, forming the sides of the hollow pattern figure f¹ in the same 25 manner as the stripe portion S is formed, while wales 4 to 9 inclusive form the plated fabric between the side portions of the figure. The arrangement of the yarns in the loops on the line 5'—5' of Fig. 2 is the same except for a possible 30 difference in the number of wales past which a particular yarn is floated.

In Fig. 6 the backing yarn b and facing yarn p are used in forming wale 1; the wrapping yarn w and backing yarn b are used in forming wales 2 and 3, while the facing yarn p is floated. The backing yarn b and facing yarn p are used in forming wales 4, 5, 8 and 9 and the backing yarn b alone is used in forming wales 6 and 7, the facing yarn p being floated past wales 6 and 7 while the wrapping yarn w is floated past wales 4 to 9 inclusive. The backing yarn b and wrapping yarn w are used in forming wales 10 and 11, while the facing yarn is floated and the backing yarn b and facing yarn p are used in forming wales 12 and 13. This arrangement forms a pattern figure as at the line 6—6 of Fig. 3 and line 6'—6' of Fig. 2, wales 2, 3 and 10, 11 forming the side portions of the figure, wales 4, 5, 8 and 9 forming plated fabric within the boundaries of the pattern figure and wales 6 and 7 forming the inner pattern figure l² of the backing yarn only. Fig. 2 along the line 6''—6'' is similar except for the change in the number of wales knit of the backing yarn alone, the pattern figure l² being 55

shown as of stepped form having its center portion wider by being knit on a larger number of needles than its end portions.

In Fig. 7, wales 1 and 2 are formed of the backing yarn *b* and wrapping yarn *w*, the facing yarn *p* being floated. Wale 3, 4, 6, 7, 9, 10 and 13 are formed of the backing yarn *b* and facing yarn *p*, wales 5 and 8 being formed of the backing yarn *b* alone, while the wrapping yarn *w* is floated past wales 3 to 10 inclusive, and the facing yarn is floated past wales 5 and 8. Wales 11 and 12 are formed of the backing yarn *b* and wrapping yarn *w*, while the facing yarn is floated past these wales. This arrangement forms a pattern figure as at the line 7'-7 of Fig. 3 and 7'-7' of Fig. 2; wales 1, 2 and 11, 12 forming the side portions of the figure; wales 3, 4, 6, 7, 9 and 10 forming plated fabric within the boundaries of the pattern figure and wales 5 and 8 forming the inner pattern figures 1² of the backing yarn alone. In this case it will be noted the figures 1² are separated by wales of plated fabric. The arrangement of line 7'-7' of Fig. 2 differs from the arrangement at line 6''-6'' of that figure in having wales of plated fabric between wales formed of the backing yarn only instead of having a plurality of adjacent wales knit of the backing yarn only; thus in the arrangement at line 7'-7' the facing yarn is taken by the needles knitting the wales 6 and 7 when the needles knitting the wales 5 and 8 float the facing yarn while in the arrangement at line 6''-6'' the needles knitting the wales 6 and 7 would continue to float the facing yarn when the needles knitting wales 5 and 8 floated the facing yarn.

In Fig. 8, wales 1 to 3 and 10 to 13 are formed of the backing yarn *b* and facing yarn *p*; wales 4, 5, 8 and 9 are formed of the backing yarn *b* and wrapping yarn *w*, while the facing yarn *p* is floated past these wales. Wales 6 and 7 are formed of the backing yarn *b* alone, while both the facing yarn *p* and the wrapping yarn *w* are floated past these wales. This arrangement forms a pattern figure as at line 8'-8 of Fig. 3 and line 8'-8' of Fig. 2, wales 4, 5 and 8, 9 forming the side portions of the figure while wales 6 and 7, knit of the backing yarn only, form the center portion 1² of the pattern figure 1².

From the drawings it is seen that knitting the backing yarn *b* and facing yarn *p* gives the fabric of the body of the stocking and the similar fabric 1¹ within the embroidery patterns; that knitting the embroidery yarn *w* and the backing yarn *b* gives the embroidery pattern and stripes, the yarn being fed in such relations that the em-

broidery yarn appears on the face of the fabric. Floating the facing yarn *p* while the wrapping yarn *w* is being fed to the needles reduces the number of yarns to be knit in one loop and reduces the tension on the yarns in drawing the loops and the danger of cutting the yarns caused thereby. Floating both the facing yarn *p* and the wrapping yarn *w*, while the backing yarn *b* only is being knit, permits of additional figures of a contrasting color being formed without necessitating the use of an additional yarn.

Selection and operation of the needles to receive and knit the various yarns may be made as shown in my co-pending application Serial No. 668,456, filed April 28, 1933, in which jacks mounted in the needle grooves are selected initially, so that the needles which take the wrapping yarns are raised to take that yarn, the jacks for the needles taking the backing yarn only are raised partly but not sufficient to affect the needles, while the jacks of the needles which take both the backing and the facing yarns are not raised at that time. Subsequently the needles which take the wrapping yarn are brought down to the level of the needles which take the backing yarn only and the jacks therefor are brought to the level of the jacks for those needles which take the backing yarn only, after which the jacks of the needles which take the facing and backing yarns are raised to move their needles to a position to take the facing yarn; after which these needles and jacks are moved to the level of the other needles and jacks, the level in which all needles take the backing yarn and the level of the jacks at that time.

What is claimed is:—

1. In a fabric formed of a backing yarn and a facing yarn knit in plating relation, a wrapping yarn knit in plating relation with said backing yarn while said facing yarn is floated to form a hollow embroidery pattern on said fabric and a pattern figure within the boundaries of said hollow embroidery pattern comprising loops formed of the backing yarn while both said facing yarn and said wrapping yarn are floated.

2. In a fabric formed of a backing yarn and a facing yarn knit in plating relation, a wrapping yarn knit with said backing yarn to form an embroidery figure having wales of plated fabric within the limits of the embroidery figure and a stepped hollow pattern figure consisting of loops of the backing yarn between wales of the plated fabric within the boundaries of the embroidery pattern and having a wale or wales of plated fabric between wales of the backing yarn.
